UNITED STATES PATENT OFFICE.

HENRY M. MORRILL, OF TEKONSHA, MICHIGAN.

CRATE.

Application filed August 9, 1924. Serial No. 731,052.

To all whom it may concern:

Be it known that I, HENRY M. MORRILL, a citizen of the United States, residing at Tekonsha, in the county of Calhoun and State of Michigan, have invented a new and useful Improvement in a Crate, of which the following is a specification.

My invention relates to a new and useful improvement in a crate and is particularly adapted for use with that class of crates used as egg carriers and has for its object the provision of a crate of this class which will be simple in structure, economical of manufacture and highly efficient in use and permit its folding upon itself so as to collapse into compact form and condition.

Another object of the invention is the provision of a crate of this class having collapsible or folding sides pivotally connected to each other and provided with a novel arrangement of attachment which is highly efficient in use and affords a means of engagement with the bottom of the crate which is loosely positioned therein, and also affords an abutment for the top of the crate to form a foundation upon which the top may rest when attached in operative position on the side members of the crate.

Another object of the invention is the provision of a crate having a separate top adapted for loose positioning upon the sides and provided with locking means for retaining the same in operative position upon the said sides.

Other objects will appear hereinafter.

The invention consists in the combination and arrangement of parts hereinafter described and claimed.

The invention will be best understood from reference to the accompanying drawings which form a part of this specification, and in which,

Fig. 1 is a perspective view of the invention showing the crate assembled,

Fig. 2 is a top plan view of Fig. 1,

Fig. 3 is a top plan view of the crate in collapsed form with the bottom and top removed,

Fig. 4 is a fragmentary sectional view illustrating the engagement of the bottom with the pivotal corner connection,

Fig. 5 is a fragmentary sectional view of Fig. 4 with the bottom removed,

Fig. 6 is a plan view of the connecting member used at corners of the side walls,

Fig. 7 is a perspective view of a modified form of the invention with the bottom in folded position,

Fig. 8 is a perspective view of a modified form of the invention with the bottom in operative position,

Fig. 9 is a fragmentary view illustrating the bottom of the modified form,

Fig. 10 is a sectional view taken substantially on line 10—10 of Fig. 9.

In the preferred form, I have shown the invention adapted to a crate which may be utilized to good advantage as an egg carrier, in which the cartons, having the individual egg compartments are positioned one upon another, so that, when the crate is in use, filled with eggs, the device serves as an efficient carrier. The construction is such that when the device is empty, it may be folded into a compact bundle so that it may be returned in shipment as a convenient bundle to handle and one occupying very little space. In this preferred form, the crate is made up from side walls, which are of equal size so as to provide a substantially square crate. The purpose of providing the crate in substantially square form is to accommodate snugly the cartons in which the eggs are packed which are generally square. Each side wall comprises a cross member 15 at the top and a cross member 15' at the bottom connecting which are a number of slats 16 which are spaced apart. The adjoining ends of the side walls at the top and the bottom are in pivotal connection by means of a metallic disc 17 which is provided with openings 18 and 18'. The disc is adapted for insertion into slits formed in the ends of the cross members 15 and 15'. These ends have a hole drilled through them so that a cotter pin may be extended therethrough and extended through the holes 18 and 18'. When the side walls are joined together in this manner, the same may be folded upon themselves in the form shown in Fig. 3.

The top and bottom are loosely positioned in the crate so that when the device is folded into the form shown in Fig. 3, the top and bottom may be strapped or otherwise fastened to the crate proper for shipment. The bottom comprises a plurality of slats 16' which are joined together by cross members 19 at opposite ends. The bottom is so constructed that it will snugly fit into the inte-

rior of the crate in close engagement with the side walls. It will be noted in Figs. 4 and 5, that the member 17, on account of its circular form and specific arrangement in connection with the ends of the cross members, projects slightly inwardly of the inner surface of the slats 16 which are positioned in the side walls. Consequently, when the bottom which is loose is pressed down to the bottom of the crate, it will engage at its four corners against the upper surface of the metallic disc 17 which serves to join the corners. In this way, the bottom of the crate is securely attached and prevented from being thrust outwardly from the sides of the crate and the load placed thereon when the crate is filled will be sufficient to keep the bottom in position. It will also be noted that the bottom is thrust downwardly between the sides with the cross members 19 downwardly positioned, so that the bottom of the crate is raised from any surface on which the crate may be placed a distance at least equal to one-half the clearance or height of the cross members 15', inasmuch as the metallic joining discs 17 are positioned intermediate or at the medial line of the member 15'.

A cover is provided for the crate which comprises a plurality of slats 20 jointed together at their ends by cross members 21. As shown in Fig. 2, this cover or top is substantially the same size as the bottom so that it fits snugly between the side walls and engages against the inwardly projecting sector of the joining discs. In assembling the cover in the crate, it is placed with the cross members positioned downwardly so that these cross members engage the inwardly engaged portions of the joining links 17 to afford a firmer structure.

It is preferred to form these cross members 21 and the slats 20 of material of such thickness as to clear the distance from the top surface of the joining link 17 and of the top surface of the cross members 15, so that, when the cover is placed in position, it will be flush or substantially flush with the top of the cross members, the upper surface of the slats being but a slight distance above the upper surface of the cross members 15. As shown in Fig. 2, the cover is provided with a handle 22 of any desired type. An eyelet 23 is mounted on one of the cross members 15 and securely fastened on the top of the cover is a wire 24 which projects beyond its edge and is adapted to enter the eyelet and project slightly beyond the edge of the side wall as shown in Fig. 2. At the opposite side, slidably positioned in an eyelet 25 is a locking wire 26, having an angularly turned portion 27. Mounted in one of the slats in alinement with the member 25 is a staple 28 which is bent over, as

shown in Fig. 2. The locking member 26 is adapted for slidable movement in the eyelet 25, so as to engage in an eyelet 29 mounted in one of the cross members 15. The structure is such that when the angularly turned portion 27 is turned upwardly, the locking member may be slid backwardly so as to ride between the separated parts of the staple 28. This will permit a removal of the cover from the side walls. When it is desired to lock the cover in position, the locking member is moved to the position shown in Fig. 2 and the angularly turned portion 27 turned downwardly, so that, the staple 28 will engage it and prevent slidable movement of the locking member 26.

In the preferred form, I have shown the invention adapted for use as a measuring basket or crate having the cross members positioned on the interior side of the crate with the slats on the outside. The bottom 30, which is constructed as the bottom already described, is provided with an eyelet 31 in which engages a broken link 32 having one end pivotally fastened in an eyelet 33, which is mounted on the cross member 15'. The construction is such that the bottom is hingedly connected to the side wall. In this structure, it is necessary that the crate be of rectangular form, so that the bottom, when folded upwardly so as to rest on its edge on the lower cross member 15', may rest snugly against the slats and engage the undersurface of the upper cross member 15. A suitable catch may be provided for retaining the bottom in this position, if desired.

While I have illustrated and described the preferred form of structure, I do not wish to limit myself to the precise form of structure shown but desire to avail myself of such variations and modifications as come within the scope of the appended claim.

Having thus described my invention, what I claim as new and desire to secure by Letters Patent is:

A crate comprising a plurality of collapsible side walls; a cover adapted for loose mounting within said side walls; a keeper projecting outwardly from one side of said cover and adapted to project beyond the outer side of said side walls when said cover is in operative position; an eyelet on one of said side walls for engaging said keeper; a slidably keeper mounted on said cover at the opposite side from said first mentioned keeper; an eyelet mounted on one of said side walls for engaging said keeper; and means for preventing the undue removal of said slidably keeper from said eyelet.

In testimony whereof, I have signed the foregoing specification.

HENRY M. MORRILL.
